VISE FOR TENNIS RACKET HEADS

Filed May 8, 1926

FIG. 1.

FIG. 2.

INVENTOR:

JOHN H. HILDEMANN,

By: Otto St. Ringer,
his Atty.

Patented Feb. 22, 1927.

1,618,532

UNITED STATES PATENT OFFICE.

JOHN H. HILDEMANN, OF LOS ANGELES, CALIFORNIA.

VICE FOR TENNIS-RACKET HEADS.

Application filed May 8, 1926. Serial No. 107,653.

This invention relates to devices by which the head end of a tennis racket may be securely clamped and held for stringing purposes.

5 One of the objects of this invention is to provide a device with an adjustable jaw to reach over the top edge of a tennis racket and which may be dropped to a certain extent to allow a finishing after a stringing 10 of the racket.

Another object is to provide a device with oppositely disposed jaws to engage in a diagonal direction as well as from opposite sides over the frame of a racket.

15 Other objects will appear from the following description and appended claims as well as from the accompanying drawing, in which—

Fig. 1 is a top plan view of a vise of a simple form, embodying the invention, part of one jaw being broken away to illustrate the relation of one jaw to the other, with the cushioning means; and

Fig. 2 is a side elevation of the bracket portion of the vise in Fig. 1, with the jaw portions shown in mid-sectional view.

For stringing rackets, the rackets must be held firmly against twisting from any angle, and, on the other hand, it must be possible to do a certain amount of finishing after the stringing while the racket should still be held in a vise, however, free around the upper edges.

As illustrated, the bracket portion 3 is designed to be secured to a bench or other suitable base. The upper end of this bracket is made in the form of one jaw member 4, having a practically level engaging face 5, set off against the top end proper, indicated at 6, and having a forwardly pointing curved engaging face 7. The level face 5 serves to support a racket placed on the vise on its underside, and the curved face serves to engage over the inside of the racket.

45 The clamping member 8 is provided with an engaging face curved oppositely to the face 7, as indicated at 9. The upper engaging face 10 is designed to overlap the face 5, and at the same time is inclined for the purpose of drawing and pressing a tennis racket against the opposite faces 5 and 7. The rear side 11 of the clamping member is also inclined for the purpose of causing a drawing and pressing in the direction of the faces 5 and 7, so that the opposing faces 5 and 7, on one side, and the faces

9 and 10 on the other side are moved towards each other in a somewhat diagonal direction. The bolt 12 is for similar reasons disposed at an angle to the upright portion 60 of the bracket, so that the knob 13 may serve to apply pressure to the clamping member 8 in this diagonal direction.

A lining 14—15 is applied to the jaw faces, and an extra heavy lining 16 is applied over the first lining 15. The lining 15—16 is disposed in a recess of which the central portion 17 is deeper, while the recess is more shallow towards the edges 18, inasmuch as this recess is provided in the flat 70 side of the clamping member 8, this flat side being merely recessed enough to take care of the curvature required for the lining.

The bracket 3 is provided with holes 19 by which the bracket may be fastened to 75 a bench or similar support.

The clamping member 8 is provided with a slot 20, allowing a dropping of the jaw to a suitable extent. This serves to provide for proper engagement while a tennis racket is firmly clamped between the opposite jaws, while it allows a dropping of the clamping member below the upper edges of the racket after the stringing, for finishing work. The front edge of the clamping member may in such a case serve fully well to engage the racket against the angularly disposed engaging faces 5 and 7.

Having thus described my invention, I claim:

1. A tennis-racket stringing head vise, consisting of oppositely disposed angular jaw members with adjusting means disposed for diagonally moving the jaws towards each other.

2. A tennis-racket stringing head vise, consisting of one jaw member with angularly disposed engaging faces, a second jaw member with engaging faces disposed to oppose the first-named faces, and controlling means for moving the oppositely disposed jaw faces in a diagonal manner.

3. A tennis-racket stringing head vise, consisting of one jaw member with angularly disposed engaging faces formed to support a racket on its under side and to engage the racket over the inner curved side, and a second jaw member with engaging faces pointing in the opposite direction and disposed to move towards the first-named faces.

4. A tennis-racket stringing vise, con-

- sisting of one jaw member with angularly disposed engaging faces formed to support a racket on one of its flat sides and to engage the racket over the inner curved side, and
- 5 a second jaw member with one engaging face curved oppositely to the first-named curved face and with another engaging face slanting upwardly so as to allow a forcing of a racket towards the flat engaging face of
- 10 the first-named jaw member while the curved faces are moved toward each other.
5. A tennis-racket stringing vise, consisting of one jaw member with angularly disposed engaging faces formed to support a racket on one of its flat sides and on one of its curved sides, a second jaw member having one engaging face curved to engage the racket from the opposite side engaged by the first-named curved face and having another face disposed inclined and to engage the racket on the opposite side of the first-stated supported side, controlling means for
- 15 moving the oppositely disposed faces in a
- 20

diagonal manner, and lining means on the engaging faces.

6. A tennis-racket stringing vise, consisting of one jaw member with angularly disposed engaging faces formed to support a racket on one of its flat sides and on one of its curved sides, a second jaw member having one engaging face curved to engage the racket from the opposite side engaged by the first-named curved face and having another face disposed inclined to engage the racket on the opposite side of the first-stated supported side, controlling means for moving the oppositely disposed jaw faces towards each other, and adjusting means whereby one of the jaw members can be dropped to a certain extent below the normal engaging position in relation to the opposite jaw.

In testimony that I claim the foregoing as my invention I have signed my name.

JOHN H. HILDEMANN.
